BRAIDING STAND

Hinkley R. Swett, Sanford, Maine

Application May 14, 1949, Serial No. 93,273

6 Claims. (Cl. 87—62)

1

This invention relates to a braiding stand, and is particularly useful in braiding such items as rug elements, although it may be used in connection with making other articles.

In making a braid, or similar article, one end of the strands making up the braid are held or anchored in a fixed position, and as the operator makes the braid, the braid lengthens; it is desirable that the braid be held taut throughout the braiding operation, and in order to accomplish that effect, it is necessary either for the operator to move back from the point of securing, or to move the point of securing away from the operator.

Heretofore there have not been satisfactory devices for holding a braid in the braiding operation. It has been customary to tie one end of the braid onto a piece of furniture, or to hold it down by a weight; then as the braid lengthened, the piece of furniture was moved away, or the weight was relocated at another point on the braid.

An object of the present invention is the provision of a braiding stand of novel construction, by the use of which the above noted objections are overcome.

Another object is the provision of a braiding stand having a novel braid holding means by the use of which the braid can be held securely in position, and as the braid lengthens in the braiding operation, it can be fed through the stand so that the braid is then held at a point closer to the place of braiding, whereby it is unnecessary either for the operator to move back from the stand or for the operator to move the stand away; the braid can thus always be held taut, and it is retained against movement in the direction toward the operator.

Still another object is the provision of a braiding stand having a novel holding clip for holding a braid.

A further object is the provision of a braiding stand having a novel braid holding means into which a braid, or the strands thereof, can be inserted at any point between the ends of the braid, whereby the braid need not be threaded through from one end.

A still further object of the invention is the provision of a braiding stand which is of simple and light construction, and accordingly easily portable, while at the same time can be easily held in position by the operator while using it.

Another object is the provision of a braiding stand which is foldable into a compact arrangement, and can be easily and readily set up for use.

2

With these and other objects in view, my invention consists in the construction, arrangement and combination of the various parts of my device whereby the objects contemplated are attained as hereinafter more fully set forth, pointed out in my claims and illustrated in the accompanying drawings, wherein:

Figure 1 is an isometric view of the braiding stand in set up position;

10 Figure 2 is an isometric view of the stand in collapsed and folded position;

Figure 3 is a sectional view taken on line 3—3 of Figure 1; and

15 Figure 4 is a sectional view taken on line 4—4 of Figure 1.

Referring now in detail to the drawings the stand is indicated as a whole at 12 and includes an upright standard 14 adapted to rest on the floor. The standard 14 is preferably rectangular in cross section but of course the particular shape is not critical and the present shape may be employed as a convenience in adapting conventionally shaped wood pieces. The whole stand may be made of wood as a matter of convenience, but 20 other materials may be employed. The lower end of the standard 14 is provided with a notch or groove 16 (Figure 2) spaced upwardly a short distance from the lower end thereof and extending transversely across the standard. The notch or groove 16 is cut only partially through the thickness of the standard as indicated in Figure 4.

Pivoted in the lower end of the standard 14 is a pair of elements 18, together forming a floor engaging member indicated generally by the numeral 19. The separate elements 18 are positioned one on either side of the standard 14 below the notch or groove 16. The elements 18 are secured to the standard 14 by means of a pin 20, the ends of which are peened over washers 22 fitted on the ends of the pin. The member 18 is thus pivotable or swingable about the pin 20. In the upright or assembled position of the stand, the member 19 is adapted to lie or rest on the floor as indicated in Figure 1.

45 Pivoted in the outer or swinging ends of the elements 18 is a tread member 24. The member 24 has cut out portions forming a tongue 26 which is fitted between the swinging ends of the elements 18 by means of a pin 28. The pin 28 may be secured in position similarly to the pin 20, the ends of the pin being peened over washers 30. The purpose of the tongue 26 is for positioning between the elements 18 while the main body of the tread member 24 is of substantially the same width as that of the elements 18 in assembled position. At the swinging or outer end

of the tread member 24 is a notch 32 forming legs or projections 34. As indicated in Figures 1 and 4, the tread member 24 is swingable to a position wherein the standard 14 is received in the notch 32 and the legs 34 straddle the standard. The legs 34 are provided with notches 36 located in such a position that when the tread member 24 is in the position shown in Figure 1, the notches face downwardly. A pin 38 is fitted in a hole extending transversely through the standard 14 at the point where the swinging end of the tread member 24 meets the standard, i. e., at a point spaced above the bottom end of the standard 14. The pin 38 has an end extending out each of opposite sides of the standard and the projecting ends of the pin are received in the notches 36 supporting the swinging end of the tread member 24 against downward movement.

The numeral 40 indicates a supporting member in the form of a transverse piece, provided with a cut out portion or notch 42 opening downwardly out of the bottom surface and extending entirely through the thickness of the piece. The notch 42 forms a reduced intermediate segment 44, and formed in the segment 44 is a vertically extending notch or groove 46 which is cut only partially therethrough, and opens out one of the flat sides. The supporting member 40 is fitted to the standard 14 in such a manner that the lower end of the standard 14 below the notch 16 is fitted in the notch 42 and the notches 46 and 16 are fitted together, and the lower edge of the piece 40 is flush with the lower end of the standard and engages the floor. A bolt 48 is fitted in a hole extending through the standard 14 and supporting member 40 for securing the two together by means of a wing nut 50. The supporting member 40 is of substantially the same thickness as the standard 14 and when the two parts are fitted together as above described, they occupy the single thickness or either of the pieces. It will be noted that the supporting member 40 extends transversely to both the standard 14 and the members 19 and 24, serving to support the standard upright.

In the upper end of the standard 14 is a novel gripping means indicated generally at 52. On one side of the upper end of the standard is a groove 54 (Figure 3), cut only partially through the thickness of the standard, forming a thin wall 56 and side legs 58. At the bottom of the groove 54 and communicating therewith is an aperture 60 cut through the thin wall 56 and communicating with the groove at the lower end of the latter. The aperture 60 is also provided with a cut out portion 62 which opens out the side of the standard in a direction radially of the axis of the aperture.

A gripping finger 64 is pivoted in the groove 54 by means of a pin 66 extending through the legs 58 and through the finger. The pin 66 is disposed substantially above the aperture 60 and actually is closely adjacent the top end of the groove. The upper end of the finger 64 is of reduced thickness, as indicated at 68, and the lower end is tapered as indicated at 70. The finger 64 extends into the projection of the aperture 60 and terminates closely adjacent the lower surface of the aperture. The tapered surface 70 forms a relatively pointed end which serves as a gripping element 70

A spring 72 is provided for biasing the gripping finger 64 to the position illustrated in Figure 3 which will be referred to as a normal position. The spring 72 is made of spring wire in the form

of a U, having a cross piece 74 fitted in a groove in the outer surface of the finger below the pin 66 and having legs 76 straddling the finger and extending upwardly between the pin 66 and the thin wall 56. The upper ends of the legs 76 extend up to adjacent the top of the groove. The spring 72 is so biased or sprung that the lower end of the spring biases the finger 64 counterclockwise or to the position wherein it is entirely within the groove 54. It might be noted that the finger 64 is of a cross-sectional contour similar to the groove 54 so that the finger does not project outwardly of the cross-sectional contour of the standard. The numeral 78 indicates a braid which may be an element of a braided rug, such as one made of a plurality of strands.

The strands from which the braid is to be made are inserted in the aperture 60 below the finger 64. When the strands are held and drawn outwardly therefrom in the direction illustrated by the straight portion extending toward the observer in Figure 1, the lower end of the finger bites into the strands, and the strands are wedged between the strands and the lower surface of the aperture 60. To insert a braid (or the strands thereof) in the aperture, the spring finger 64 is rotated so that the lower end extends to the left as shown in dotted lines in Figure 3. This is done by gripping the upper end 68 of the finger and the upper end of the thin wall 56 and squeezing together, swinging the lower end of the finger outwardly. The braid is then inserted, and when the finger is released, the lower end of the finger springs back under the action of the spring 62 and grips the braid. As the operator works on the braid, the tendency is to draw the braid toward the operator. This action wedges the braid tightly between the finger and the aperture. When a length of braid has been made, it is desired that it be gripped in a new position and for this purpose the braid is simply drawn through the aperture in the direction away from the observer as illustrated in Figure 3. The finger springs outwardly, permitting the braid to be drawn through the aperture in the manner just referred to.

The operator places his foot on the tread member 24 which secures the stand in its desired position. The downward pressure on the tread member 24 is restrained by the notches 36 fitting over the pin 38. The tread member is thus in locked position and the stand as a whole is readily retained in its set up position.

The cut out portion 62 of the aperture 60 enables the braid to be inserted and removed from the aperture in a convenient manner and it is not necessary to thread the braid through the aperture from one end.

The stand can be readily collapsed and folded into a compact assembly. The tread member 24 is lifted off of the pin 38; the supporting member 40 can be readily removed from the standard by removing the wing nut 50; then the members 19 and 24 can be moved to the position illustrated in Figure 2 wherein they extend generally longitudinally of and closely adjacent the standard with the supporting member 40 fitted therebetween. The whole assembly then occupies only a small space and is fitted or folded in a compact arrangement. For all practical purposes all of the members making up the stand are of the same width although the standard is not as wide as the other members, being narrower only to the extent of the thickness of the elements 18. All of the members for that reason make up a compact mass

which can be readily packed and contained in a carton.

It will be seen from the foregoing that a light and readily portable stand has been produced. The stand can be readily effectively anchored in position by the pressure of the foot of the operator on the tread member 40, and the braid can be secured at successively new points as the braid lengthens so that the operator need not move back from the point of securement nor move the point of securement away from him.

While I have herein shown and described a preferred embodiment of my invention, manifestly it is susceptible of modification without departing from the spirit and scope thereof. I do not, therefore, wish to be understood as limiting my invention to the precise form herein disclosed, except as I may be so limited by the appended claims.

I claim as my invention:

1. In a stand of the character disclosed, the combination comprising, an upright standard, means in the upper end of the standard for gripping a braid, a floor engaging member pivoted on the lower end of the standard and movable to a position extending laterally from the standard, a tread member pivoted on the extended end of said floor engaging member, and means for detachably connecting the extended end of the tread member and the standard at a point above the lower end of the standard.

2. In a stand of the character disclosed, the combination comprising, an upright standard, means in the upper end of the standard for gripping a braid, a floor engaging member pivoted on the lower end of the standard and movable to a position extending laterally from the standard, a projection on the standard spaced upwardly from the lower end, and a tread member pivoted on the extended end of the floor engaging member, said tread member having a notch adjacent its extended end, the notched end being swingable to a position adjacent said projection, and the notch being adapted to receive said projection, whereby said tread member becomes a rest for the foot of the operator.

3. In a stand, an upright standard, a floor engaging member pivoted on the lower end of the standard, a tread member pivoted on the swinging end of said floor engaging member, and means for detachably locking the swinging end of the tread member to the standard at a point above the lower end of the standard, and a supporting member removably secured to the lower end of the standard, said supporting member being disposed transverse to the standard and to said floor engaging member.

4. In a stand, an upright standard, a floor engaging member pivoted on the lower end of the standard, a tread member pivoted on the swinging end of said floor engaging member, and means for detachably locking the swinging end of the tread member to the standard at a point above the lower end of the standard, and a supporting

member removably secured to the lower end of the standard, said supporting member being disposed transverse to the standard and to said floor engaging member, said floor engaging member and tread member being foldable to a position extending longitudinally of and closely adjacent the standard, said standard, floor engaging and tread members, and said supporting member all being of similar width whereby the supporting member can be fitted with the remaining members in a compact arrangement.

5. In a device of the character disclosed, an upright standard, a pair of floor engaging members pivoted on the lower end of the standard, said floor engaging members being disposed on opposite sides of the standard, a projection on the standard above the lower end thereof, a tread member pivoted in and between the swinging ends of said floor engaging members, the swinging end of said tread member being swingable to a position adjacent the standard, the swinging end of said tread member having a recess adapted to receive said standard and having a notch adapted to receive said projection, and a supporting member removably secured to the lower end of the standard, said supporting member being disposed transverse to the remaining elements of the stand.

6. In a foldable and portable braiding stand, the combination comprising, an upright standard adapted to rest on the floor, the upper end of said standard having an aperture therethrough adapted for receiving a braid, a gripping finger pivoted on the standard and having its swinging end extending into the projection of the aperture, said finger being adapted to engage a braid in the aperture and yield in one direction for permitting the braid to be drawn through the aperture in that direction and being non-yieldable in the opposite direction for preventing the braid from being drawn through the aperture in that direction, a floor engaging member pivoted on the lower end of the standard, a tread member pivoted in the swinging end of said floor engaging member, means for detachably interlocking the swinging end of the tread member and the standard at a point above the lower end of the standard, and a supporting member removably connected to the lower end of the standard, said supporting member being disposed transverse to the standard and floor engaging member.
